CLAIM

The ornamental design for a display device with icon set, as shown.

DESCRIPTIONFIG. 1 is a front view of a first icon belonging to the claimed icon set, showing our new design; and,
FIG. 2 is a front view of a second icon belonging thereto.
The broken lines shown in FIGS. 1 and 2 show portions of a display screen and form no portion of the claimed design.**1 Claim, 2 Drawing Sheets**(56)
